Thomas Boyd

United States Patent Office.

THOMAS BOYD, OF CAMBRIDGEPORT, MASSACHUSETTS.

Letters Patent No. 60,677, dated January 1, 1867.

VENTILATOR FOR MINING SHAFTS, BUILDINGS, &c.

The Schedule referred to in these Letters Patent and making part of the same.

TO ALL WHOM IT MAY CONCERN:

Be it known that I, THOMAS BOYD, of Cambridgeport, in the county of Middlesex, and State of Massachusetts, have invented certain improvements in Ventilators for Buildings, Mining Shafts, &c.; of which the following is a full, clear, and exact description, reference being had to the accompanying drawings, making part of this specification, in which—

Figure 1 is an elevation of my improved ventilator.

Figure 2 is a central vertical section through the same.

Figure 3 is a plan of the lower portion of the same.

My invention consists in a ventilator for buildings, mining shafts, &c., provided with a metallic chamber (either with or without glazed orifices,) for conducting the heat of the sun's rays to the air within the same, so as to produce an upward current of air through the ventilator. Another part of my invention consists in making a ventilator which will operate in the absence of the sun's rays, by giving a rotary motion to the air within the same, by means of currents introduced from the outside, assisted by artificial heat introduced into the ventilator.

To enable others skilled in the art to understand and use my invention, I will proceed to describe the manner in which I have carried it out.

In the said drawings, A is a chamber within the main body or outer casing of the ventilator, which may be globular, hexagonal, or of any suitable form. B is the main pipe through which the air is drawn up from the apartment below; around this pipe, B, and communicating with the external air, are arranged a series of short tubes, a, which are inclined as seen in figs. 2 and 3, so as to impart a rotary motion to the upward current of air, and thus increase its strength and velocity. Three tubes, b, bent at their upper ends and communicating with the external air, are also arranged within the chamber, A; these tubes discharging the air with a rotary motion in the same direction as the tubes, a, below, and assisting the current as it passes to the main outlet, C. The upper half of the main body of the ventilator is provided with a series of lenses, c, placed at suitable distances apart over its entire surface, and the heating rays of the sun passing through the lenses, are to a considerable extent concentrated directly on to a hollow metallic ball, D, (painted black or other dark color,) which is suspended in the centre of the chamber, A, as will be more particularly described hereafter, and is provided with an opening, 5, at the bottom, and perforated at the top at 6, as seen in fig. 2. The ball, D, is thus heated to a considerable degree, as are also, in a lesser degree, the other metallic surfaces within the chamber, A; and the radiation of heat from these surfaces causes the air within the chamber, A, to become rapidly and continuously heated so long as the sun shines, producing a strong upward current as required. The upper portion of the main body of the ventilator, around the discharge opening, C, is notched in the ordinary manner, and above this opening is placed a cap, E, which is supported on a pipe, F, which passes through it, and is secured at its lower end to a ring, d, which is supported by the hollow rods, b. The under surface of the cap, E, is made slightly convex, so as to deflect the air and facilitate its discharge from the opening, C, and this under surface is made of metal or other material capable of receiving and retaining a smooth polished surface, so as to present no obstruction to the air coming in contact with it from the opening, C. Within the pipe, F, are arranged a series of twisted or grooved tubes, e, and in the centre is secured a twisted or grooved tube, f, which extends up above the top of the pipe, F, as seen in fig. 2. The air, as it passes up the main pipe, B, first comes in contact with the heated ball, D, a portion passing up through its interior and into the central twisted tube, f, (where the draught is the greatest,) and another portion passing around the exterior surface of the ball, and up through the twisted tubes, e, to the discharge opening at the top of the pipe, F, which is notched as seen in fig. 2; and these tubes, e, f, together with the tubes, a, b, above mentioned, serve to increase the strength of the upward current and cause the ventilator to operate in the absence of the sun's rays. To still further aid ventilation in the absence of the sun's rays, artificial heat may be introduced from a furnace or other heating apparatus, by means of a pipe or pipes, 7, (fig. 2,) into the hollow ball, D, and chamber, A, so as to heat the same and increase the upward current. The upper end of the pipe, F, where the air is discharged, is covered by a conical cap, G, which rests on a flange, g, on the tube, f, and is so hung and balanced, that a slight current of air will cause it to vibrate, and close the side toward the wind.

and open, in a corresponding degree, the opposite side so as to permit the air to be freely discharged on that side. This cap, G, is furnished with lenses, h, the heat produced by which increases the force of the upward current as before described. The upper surface of the cap, E, is made convex, so as to facilitate the discharge of the air from beneath the cap, G. To the top of the tube, f, is secured a hollow ball, H, the upper portion of which is also provided with lenses, i, and at the top of this ball, H, is an opening, j, which forms a discharge orifice for the air passing up through the tube, f, and this opening is surmounted by a cap, I, supported on rods, k, the under surface of the cap being polished and slightly convex to facilitate the discharge of the air. Three lenses, l, are set in the cap, I, and these lenses, together with those in the ball, H, serve to increase the force of the upward current of air in the manner before specified. On top of the cap, I, is a ball, m, into which is screwed the end of a long rod, n, to the lower end of which is screwed the hollow ball, D, which is thus suspended in the centre of the chamber, A, as required. Instead of lenses, as above described, plain glass or other translucent material may be employed if preferred. I do not confine myself to the number of twisted tubes, e f, as one or more may be employed as may be deemed preferable; the tubes a b may also be used in connection with the tubes e f, or either may be used separately; and instead of twisted tubes, smooth tubes may be used, as they answer a good purpose in some localities. The chamber, A, may be of metal or other conducting material without the glazed orifices above described, relying upon the power of the sun to heat the outer chamber only. To do this more effectually, I paint the outside black, or some other dark color, to attract the heating rays of the sun.

The two portions of my invention, above described, may be advantageously combined in the same ventilator, or either of them may be used separately if desired.

Claim.

What I claim as my invention, and desire to secure by Letters Patent, is—

The method of ventilating buildings, etc., by the use of a metallic chamber conducting the heat of the sun's rays to the air within the same, with or without glazed orifices, operating substantially as described.

I also claim the combination of the above, described metallic chamber having glazed orifices, with an interior metallic surface, whether globular or other form, so arranged as to receive the heating rays of the sun and radiate the heat to the air within the chamber substantially as set forth.

I also claim the employment of orifices in the metallic chamber filled with plain glass, lenses, or other translucent material, to allow the direct transmission of the sun's rays to the air within the said metallic chamber, operating substantially as described.

I also claim, in combination with the above, the vibrating cap G, operating substantially as described for the purpose set forth.

I also claim the use of the tubes a b, so arranged as to produce a rotary motion of the air within the chamber A, substantially as described.

I also claim the use of one or more twisted or smooth tubes e f, in combination with the chamber A, substantially as and for the purpose set forth.

I also claim introducing artificial heat from a furnace or other heating apparatus, into the hollow ball D, and chamber A, so as to heat the same and increase the upward current in the absence of the sun's rays, substantially as described.

THOMAS BOYD.
